UNITED STATES PATENT OFFICE.

WILLIAM N. BEST, OF NEW YORK, N. Y., ASSIGNOR OF ONE-THIRD TO JOHN H. BEST AND ONE-THIRD TO EZRA BEST, OF QUINCY, ILLINOIS.

COMBUSTION-CHAMBER FOR GAS OR OIL STOVES.

No. 865,992.

Specification of Letters Patent.

Patented Sept. 17, 1907.

Application filed July 11, 1906. Serial No. 325,583.

To all whom it may concern:

Be it known that I, WILLIAM N. BEST, a citizen of the United States, and a resident of the city of New York, borough of Brooklyn, in the county of Kings and State of New York, have invented a new and Improved Combustion-Chamber for Gas or Oil Stoves, of which the following is a full, clear, and exact description.

This invention relates to improvements in combustion chambers for gas, oil, or similar stoves, the object being to provide a cheap and durable device for accomplishing important factors in the improvement of gas-stove operations. First: To provide a means by which the heat will be increased to assist combustion, and siphon—by the agency of the gas pressure through the burner—sufficient air requisite to promote combustion in the chamber, and to provide means for the expansion of the consuming gases. Second: To effect the highest economy in the fuel by controlling and confining the heat in the chamber, not permitting generated heat to go to waste by passing out under the stove. Third: To provide a combustion chamber of such proportions and form of construction that the generated heat will be directed against the object to be heated.

Other objects of the invention will appear in the general description.

I will describe a combustion chamber for gas stoves, embodying my invention, and then point out the novel features in the appended claims.

Reference is to be had to the accompanying drawings forming a part of this specification, in which similar characters of reference indicate corresponding parts in all the figures.

Figure 1 shows in plan, a combustion chamber for a gas stove, embodying my invention; Fig. 2 is a section on the line 2—2 of Fig. 1; Fig. 3 is a section on the line 3—3 of Fig. 1; Fig. 4 is a section on the line 4—4 of Fig. 1; and Fig. 5 is a section on the line 5—5 of Fig. 2.

Referring to the drawings, 10 designates the top of an ordinary gas stove having an opening in which the combustion chamber is arranged, and supported in the stove is an ordinary circular burner 11. The combustion chamber consists of a metal casing 12, the well of which is flared upward and outward, and the burner as clearly indicated in Fig. 2, may be located near the lower open end of said casing.

On the periphery of the casing, at the upper end are outwardly extended lugs 13 which engage in recesses 14 formed in the stove top, thus preventing any rotary displacement of the chamber with relation to the stove top. The bottom of the chamber is provided with an

inwardly extended annular flange 15 from which spaced ribs 16 extend upward to the top of the chamber.

Arranged in the spaces between the ribs 16 is a packing or lining 17 of a refractory material such, for instance, as clay, asbestos or the like; this will aid materially in retaining the heat within the chamber. Removably supported on the upper end of the chamber is a spider or grate consisting of a ring 18 having inwardly 60 and downwardly inclined fingers 19, upon which the vessel to be heated is supported. The ring 18 is provided on its under side with recesses 20 for receiving the lugs 13 and permitting the ring to rest closely upon the upper portion of the chamber, thus preventing 65 heat from passing between said parts and compelling the same to pass upward against the bottom of the vessel to be heated, and out between the outer ends of the fingers, as said fingers are raised somewhat from the ring. By inclining the fingers downward, or making the spider convexed it will accommodate vessels having rounded bottoms. By inclining the wall of the chamber, the products of combustion will be allowed to expand as they pass upward and strike upon all parts of the vessel bottom. 75

While I have shown the device as circular, it is to be understood that it may be otherwise shaped, without departing from the spirit of my invention; and further, it may be a fixed portion of the stove instead of removable as indicated in the drawings. 80

Having thus described my invention I claim as new, and desire to secure by Letters Patent:

1. A combustion chamber for liquid or gaseous fuel burners, consisting of a casing having an inwardly-directed flange adjacent its lower end and a plurality of inwardly directed spaced ribs extending upward from said flange to the upper portion of the casing, the space between said ribs being widest adjacent the casing and narrowing toward the center of the chamber, and refractory material in the space between the ribs. 90

2. A combustion chamber for liquid or gaseous fuel burners, consisting of an inverted, conical, imperforate casing having a wall provided with a plurality of spaced ribs extending inwardly therefrom, the spaces between ribs being greater adjacent the casing wall than at the inner surfaces of said ribs, refractory material within the space between the ribs, and means adjacent the ends of the casing for preventing the longitudinal displacement of the refractory material. 95

3. The combination with a liquid or gaseous fuel burner, of an imperforate casing surrounding the same, a plurality of blocks of refractory material secured to the inner surface of said casing, means integral with the casing and in engagement with one end and the opposite sides of each block for preventing the displacement of said blocks, and a spider supported above said burner and having downwardly-inclined radial fingers. 100

4. A combustion chamber for liquid or gaseous fuel burners, comprising a casing having its wall inclined upward

and outward and having an annular flange at the inner and lower end of the casing, spaced ribs extending inwardly from said casing, and refractory blocks in the spaces between the ribs, the sides of the ribs and the sides of the blocks facing toward the interior of the chamber presenting a smooth uninterrupted surface.

5. The combination with a gas or oil stove having an opening and recesses formed in the top, of a combustion chamber consisting of a casing having its wall inclined upward and outward, lugs on the upward end of said

casing, for engaging in said recesses, and a spider having a ring portion provided with recesses for receiving said lugs.

In testimony whereof I have signed my name to this specification in the presence of two subscribing witnesses. 15

WILLIAM N. BEST.
